SPARKING PLUG

William John Vincent, Cardiff, Wales

Application March 3, 1937, Serial No. 128,851
In Great Britain March 3, 1936

1 Claim. (Cl. 123—169)

This invention relates to improvements in 5
sparking plugs for internal combustion engines,
and more particularly to sparking plugs in which
a heating resistance element adapted for con-
nection to a low tension battery is incorporated
with the plug for the purpose of heating the
sparking plug and driving off condensation prod-
ucts and facilitating ignition. The present in-
vention has for an object an improved construc-
tion of sparking plug of this type.

In accordance with the invention, a sparking 10
plug comprises in combination with a plug body
a central electrode, said central electrode hav-
ing a lower free end extending within said plug
body, a conducting sleeve surrounding and in-
sulated from said central electrode, a conduct-
ing bush surrounding and insulated from said
conducting sleeve, a gland nut engageable with
said bush to hold said bush in said plug body, a
resistance coil disposed around and spaced from
the lower free end of said central electrode, said
resistance coil being adapted to be heated from
a source of low tension current, the resistance coil
being connected at one end to said conducting
sleeve and at the other to said bush and means
remote from the plug body providing connec-
tion between said conducting sleeve and the
source of low tension current.

The single figure of the accompanying drawing
30 shows in cross section a sparking plug construct-
ed in accordance with the present invention.

Referring now to the drawing, 1 denotes the
tubular plug body, and 2 the central or main
electrode. 35 The shank of the central electrode 2 is sur-
rounded over the major portion of its length by
an insulating sleeve 4 embraced by a metal con-
ducting sleeve 11 to which is attached between
the fixed nut 3 and the locking nut 15, a low ten-
sion conductor 12. The high tension conductor 9
is clamped to the central electrode 2 by means
of a fixed nut 10 and a locking nut 16. Suitable
insulating members 17 and 18 are mounted under
40 the fixed nuts 3 and 10, respectively. The con-
ductors 9 and 12 may be led to any convenient

source of electric current such as a battery (not
shown), the current being controlled from any
convenient position such as the dash-board of a
car. The sleeve 11 is surrounded by insulation 13
embraced by a flanged conducting bush 5 engaged 5
by the gland nut 6, threaded into the plug body 1.
To the inner end of the sleeve 11 is attached one
end of a resistance coil element 8a surrounding
the inner end portion of the central electrode 2
within the pocket 7 so that, when the sparking 10
plug is in use, combustible gases may enter the
pocket 7 and be ignited by the coil 8a in the event
of failure of the sparking plug to ignite such
gases. 14 denotes the earthed electrodes of the
plug. The resistor coil 8a is earthed by connec- 15
tion to the bush 5.

As will be clear, the resistor coil 8a in the po-
sition shown serves not only to maintain the plug
points free from moisture and to heat up the
plug in order to facilitate starting, but serves 20
also as a preheater for the combustible gases en-
tering the pocket 7.

The resistor coil 8a, while being exposed to the
combustion gases, is shielded by the plug body 1
from fuel spray when used in engines operating 25
under so-called solid-injection fuel systems.

I claim:

A sparking plug comprising in combination
with a plug body, a central electrode, said central
electrode having a lower free end extending with- 30
in said plug body, a conducting sleeve surround-
ing and insulated from said central electrode, a
conducting bush surrounding and insulated from
said conducting sleeve, a gland nut engageable
with said bush to hold said bush in said plug 35
body, a resistance coil disposed around and spaced
from the lower free end of said central electrode,
said resistance coil being adapted to be heated
from a source of low tension current, the resist-
ance coil being connected at one end to said con- 40
ducting sleeve and at the other to said bush and
means remote from the plug body providing connec-
tion between said connecting sleeve and the
source of low tension current.

WILLIAM JOHN VINCENT.
